United States Patent [19]

Kajita

[11] Patent Number: Des. 330,197

[45] Date of Patent: ** Oct. 13, 1992

[54] ELECTRONIC COMPUTER

[75] Inventor: **Takashi Kajita**, Tokyo, Japan[73] Assignee: **Kabushiki Kaisha Toshiba**,
Kanagawa, Japan[**] Term: **14 Years**[21] Appl. No.: **479,587**[22] Filed: **Feb. 13, 1990**

[30] Foreign Application Priority Data

Aug. 30, 1989 [JP] Japan 1-31312
